(57) **CLAIM**

We claim the ornamental design for a solar-powered refrigerated cooler, as shown and described.

DESCRIPTION

FIG. 1 is a perspective view of a solar-powered refrigerated cooler showing our new design;
FIG. 2 is a front elevational view thereof;
FIG. 3 is a rear elevational view thereof;
FIG. 4 is a right side elevational view thereof, the left side elevational view being a mirror image thereof;
FIG. 5 is a top plan view thereof; and,
FIG. 6 is a bottom plan view thereof.
